(57) **CLAIM**

The ornamental design for a container for use in a washing process, as shown and described.

DESCRIPTION

FIG. 1 is a perspective view of a container of the present invention;

FIG. 2 is a front view of the container of FIG. 1;

FIG. 3 is a back view of the container of FIG. 1;

FIG. 4 is a side view of the container of FIG. 1;

FIG. 5 is the other side view of a container of FIG. 1;

FIG. 6 is a top view of the container of FIG. 1; and,

FIG. 7 is a bottom view of the container of FIG. 1.

The broken lines are included for the purpose of illustrating a portion of the container that forms no part of the claimed design.
